(57) **CLAIM**

The ornamental design for a protective cover for a handbag, as shown and described.

DESCRIPTION

FIG. 1 is a front, right and top perspective view of the protective cover for a handbag showing the new design; FIG. 2 is a front elevation view thereof, the rear elevation view being a mirrored image thereof;

FIG. 3 is a right side elevation view thereof, the left side elevation view being a mirrored image thereof;

FIG. 4 is a top plan view thereof; and,

FIG. 5 is a bottom view thereof.

The front and rear panels, left and right panels, and bottom panel of the protective cover for a handbag are made of a transparent material.
